E. E. THOMAS.
PNEUMATIC WATER LIFTING DEVICE.
APPLICATION FILED JAN. 25, 1917.
1,363,443.

Patented Dec. 28, 1920.

Edwin E. Thomas
By *H. P. Litzengre* Inventor,
Atty.

UNITED STATES PATENT OFFICE.

EDWIN E. THOMAS, OF PORTLAND, OREGON, ASSIGNEE TO H. O. TENNEY, OF PORTLAND, OREGON.

PNEUMATIC WATER-LIFTING DEVICE.

1,363,443.

Specification of Letters Patent. Patented Dec. 28, 1920.

Application filed January 25, 1917. Serial No. 144,439.

To all whom it may concern:

Be it known that I, EDWIN E. THOMAS, a citizen of the United States, residing in the city of Portland, county of Multnomah, and 5 State of Oregon, have invented certain new and useful Improvements in Pneumatic Water-Lifting Devices, of which the following is a specification.

My invention relates to pneumatic water 10 lifting devices of that class adapted to be placed in a well, or submerged in a body of water and adapted to be operated by means of compressed air, controlled by a float, for the purpose of forcing water from said 15 well or body of water to a higher elevation.

One of the principal objects of my invention is to provide a simple, practical and automatic pneumatic water lifting device of such construction that it can be used to 20 lift water from any body of water which is of sufficient depth to receive the device, thus making it capable of adaptation to any location and for any capacity.

Other objects and advantages will be apparent from the following description of 25 one practical embodiment of the invention, taken in connection with the accompanying sheet of drawings illustrating the same, and in which,—

30 Figure 1 is a side elevation of a complete device with the outside casing shown in vertical section;

Fig. 2 is an enlarged, sectional view of the upper end of the device;

35 Fig. 3 is a side elevation looking at the right hand side of the device, as shown in Fig. 1; and

Fig. 4 is a reduced, horizontal, sectional view taken on line 4—4 of Fig. 2.

40 My invention, as here illustrated, is particularly adapted for use in wells, and comprises an outer casing 1, adapted to be let down into a well, and provided at its lower end with an inlet check valve 2, for admitting water to the lower end of said casing and for preventing its escape therefrom. Said casing is provided at its upper end with a top cap 3, upon and through which is mounted the controlling mechanism of 45 the device. Mounted through said top cap 3, is a water pipe 4, provided at its upper end with a check valve 5, the lower end of said pipe terminating a short distance above the inlet check valve 2, in said casing 1. Slidably mounted around said pipe 4, within

said casing 1, is a long float member 6, adapted to fit loosely around the pipe 4, as will be clearly understood from Fig. 4. Also mounted through said top cap 3, is a valve operating rod 7, which also passes through 60 said float 6, and to this end said float is provided in its side with a longitudinally extending groove, or socket 8, as clearly shown in Fig. 4. Said valve-operating rod 7, is provided at its lower end with a knob 9, 65 and at its upper end, within said casing, with a corresponding knob 10, said knobs being adapted to be engaged by said float member 6. Said operating rod 7, operates through a suitable packing 11, in said top 70 casing 3, and is provided at its upper end with nuts 12 and 13, and with two coiled springs 14 and 15, bearing at their extreme opposite ends against the nuts 12 and 13, and at their adjacent ends against washer-like members 16 and 17, between which a valve-operating lever 18, is connected to said operating rod 7, as clearly indicated in Fig. 2. Said valve lever 18, is connected with a valve member 19, turning within the 80 valve casing 20, which is supported on the top cap 3, as at 21, said valve casing being connected by means of a pipe 22, through the cap 3, with the casing 1, and also having connected therewith an air pipe 23, 85 through which air under pressure can be supplied through said valve casing and the pipe 22, to the upper end of the main casing 1. Said valve casing also has an exhaust port 24, adapted to be connected with 90 said pipe 22, when the valve lever 18, is moved downwardly at its outer end, in a manner and for a purpose hereinafter again referred to.

The operation of my invention may be 95 briefly described as follows: With the parts in the positions as shown in Figs. 1 and 2, the casing 1, is supposed to be filled with water which has entered said casing through the inlet check valve 2, carrying the float 6, 100 to the top of the casing 1, where it is about to engage the knob 10, on the operating rod 7, in such manner that it will raise said operating rod 7, and thus raise the valve lever 18, and turn the valve member 19, so as to 105 open communication between the air supply pipe 23, and the pipe 22, leading into the top of the casing 1, above the float 6. This air pressure within said casing above the water will force the water into the lower 110

end of the pipe 4, and up through the same to the place of delivery, the float 6, sinking as the water in the casing 1, is thus forced out through the pipe 4. As said float 6 approaches the bottom of the casing 1, it engages the knob 9, on the valve rod 7, in such a manner as to move it downwardly, thus moving the valve lever 18 downwardly, and turning the valve member 19, so as to open communication between the pipe 22, and the exhaust outlet 24, in said valve casing 20, at the same time cutting off the air supply through the pipe 23. With the exhaust 24 open, the air in the casing 1, passes out freely as another supply of water runs in through the inlet check valve 2, again raising the valve 6, to the top of the casing 1, where its operation is as before described.

Attention is called to the fact that with the coiled springs 14 and 15, on the valve-operating rod 17, above and below the end of the valve lever 18, said valve lever is given a quick movement in either direction, for the springs will be partially compressed by the movement of the float 6, against the knobs 9 and 10, on the operating rod 7, before said valve lever 18 is started. As soon as the tension of either of the springs 14 or 15, as the case may be, becomes sufficient to overcome the friction of the valve lever 18, it will be moved quickly, and thus quickly open full communication between the pipes 23 and 22, or between the pipe 22 and the outlet port 24.

It will thus be seen that with a supply of air under pressure connected to the pipe 23, my device will operate continuously and automatically to lift the water from the well through the pipe 4 and the check valve 5, and thence to its place of delivery. The broken lines in Figs. 2 and 4 indicate a well casing.

I am aware that changes can be made in the details of my invention, here shown for purposes of illustration, without departing from the spirit thereof, and I do not, therefore, limit the invention to these details, except as I may be limited by the hereto appended claims.

50 I claim:

1. A pneumatic water lifting device of the character referred to, comprising in combination with a well, a casing having a

valve-controlled inlet at its lower end to permit inflow and prevent outflow, a water supply pipe extended down into said casing and opened at its lower end, a float around said pipe within said casing, said float substantially filling the space around said pipe within said casing for the length of said float, a valve-operating rod in said casing and through said float adapted to be moved in opposite directions as said float reaches the opposite limits of its movement within said casing, means for connecting a source of air under pressure with said casing outside of said pipe, a valve with valve lever interposed in said connections for cutting off said air supply, said valve having an exhaust port adapted to be put into communication with said casing when the air supply is cut off therefrom, said valve-operating rod operating through said valve lever, and yieldable connections between said valve-operating rod and said valve lever, whereby said valve lever is yieldingly moved in opposite directions by said valve rod and said float, substantially as described.

2. In a water lifting device, in combination, a tubular casing having a valve-controlled inlet at its lower end, a discharge pipe extended down into said casing, and open at its lower end, a float moving up and down around said discharge pipe within said tubular casing, a three-way valve controlling the inlet and exhaust from said tubular casing, said valve having an operating lever, an operating rod extending down into said tubular casing and having means at its opposite ends for movement by said float as said float rises and falls in said tubular casing, said rod operating through the outer end of said valve lever, spring connections at opposite sides of said valve operating lever, on said rod and with said rod, whereby the movement of said rod up and down, yieldingly moves said lever up and down, substantially as and in the manner described.

Signed at Portland, Multnomah county, Oregon, this 2nd day of January, 1917.

EDWIN E. THOMAS.

In presence of—

I. M. GRIFFIN,
J. C. STRENG.
